UNITED STATES PATENT OFFICE

ANDREW T. MACCOY, OF BOSTON, MASSACHUSETTS

PRINTING TELEGRAPH

Application filed December 9, 1929. Serial No. 412,751.

This invention relates to printing telegraphs and pertains more especially to character printing apparatus for selectively transmitting and receiving, for example, letter and numeral characters and the like, giving press reports, stock quotations and similar information. The invention resides more particularly in a receiving and printing mechanism, and the primary object thereof is to provide a speedier and simpler device for this purpose.

Devices of this nature which print on a narrow tape commonly employ one or more character printing wheels. Means is provided for rotating this wheel or wheels and heretofore it has been considered necessary to arrest the wheel while performing each printing operation. It is an object of my invention to provide an improved receiving and printing mechanism wherein the printing operation is performed without stopping or effecting the rotation of the wheel, the speed of operation thereby being considerably increased.

Printing telegraphs of this nature commonly employ two type wheels, one carrying alphabetical type and the other numeral type, and two press members respectively cooperating with the wheels. Printing from these wheels requires quick selection and operation of these members. A further object of my invention resides in providing electrically controlled means comprising a pair of series and oppositely connected electromagnets respectively controlling the members and cooperating mechanical means for quickly operating the members to perform the printing operation.

Among other objects of my invention are the provision of improved means for feeding the tape and improved means for automatically controlling the starting and stopping of the printing mechanism.

With the above and other objects in view, as will become more apparent as the description proceeds, my invention consists in the features of construction and operation set forth in the following specification and illustrated in the accompanying drawings. In such drawings I have illustrated certain spe-

cific embodiments of my invention but it will be understood that the invention can be otherwise embodied and that the drawings are not to be construed as defining or limiting the scope of the invention, the claims appended hereto being relied upon for that purpose. 55

Referring to the figures of the drawings: Figure 1 is a front elevation of my improved printing telegraph.

Fig. 2 is an end elevation thereof. 60

Fig. 3 is a fragmentary sectional view showing a portion of the driving connections.

Fig. 4 is a sectional view taken approximately on line IV-IV of Fig. 2. 65

Fig. 5 is a rear elevation.

Fig. 6 is a diagrammatic view particularly showing the wiring circuits.

In the drawings, 1 indicates the base of my improved printer and 2 a roll of tape 3 mounted on a support 4. The end of this tape is led over a bracket 5 and beneath a pair of type wheels 6 and 7, the wheel 6 having mostly numeral type and the wheel 7 having mostly letter type. A resilient stripper 8 supported at 9 extends horizontally above the tape beneath the wheels and normally holds the tape slightly out of contact with the wheels. The free end of the strip is gripped midway between its edges by a pair of knurled feed wheels 10 and 11. An inking roller 12 supported on a pivoted arm 13 rests on the type wheels. 75

The type wheels 6 and 7 and tape feed wheels 10 and 11 are driven by a motor 14 mounted on the base 1. A spiral gear 15 on the motor shaft is in mesh with a spiral gear 16 on a shaft 17.

A pinion 18 on the shaft 17 is in mesh with a gear 19 fast on a shaft 20. A gear 21 loose on the shaft 20 is frictionally held between a pair of friction plates 22 and 23, a spring 24 acting to force a collar 25 against the plate 22 and hold these parts in frictional contact. The collar or disc 25 is pinned at 26 to rotate with the shaft. 90

The tape feed wheels 10 and 11 are driven from the gear 21 as follows. The gear 21 is in mesh with a pinion 27 mounted on a stud 27' and the pinion 27 is in mesh with a pin- 100

ion 28 on a shaft 29. The feed wheel 10 is mounted on the opposite end of this shaft. The feed wheel 11 is mounted on the outer end of a sleeve 30 rotatable on a stud 31 carried by 5 an arm 32 pivoted at 33. A gear 34 is carried on the inner end of the sleeve. The feed wheel 11 and gear 34 are so located as to respectively engage the cooperating feed wheel 10 and a pinion 35 on the shaft 29 when the 10 arm is in its normal position (Fig. 1). A leaf spring 36 aids gravity in holding these elements in proper working contact. The feed wheels are therefore driven in the tape feeding direction when permitted by the following 15 means.

A ratchet wheel 37 fast on the shaft 29 is normally engaged by a pawl 38 carried on a shaft 39. A spring 40 on this shaft normally holds the pawl engaged with the ratchet wheel in a manner preventing rotation of the feed wheels. Beneath the shaft 39 is a pair of electro-magnets 41 and the armature 42 thereof is mounted on this shaft. The arrangement is such that when the magnet 25 is energized the attraction of the armature withdraws the pawl and permits the shaft 29 to turn in the tape feeding direction. The spring 40 however quickly returns the pawl in a manner permitting only one tooth of the ratchet to escape. This movement feeds the tape the proper distance for one printing character thereon.

The gear 19 is in mesh with a gear 43 loose on a shaft 44, the shafts 17, 20, 29, 39 and 44 35 all being supported in a frame comprising front and rear members 45 and 46. The gear 43 is held frictionally between a pair of friction plates 47 and 48. The plate 47 rests against a gear 49 fast on the shaft 44 and a 40 spring 50 on the shaft holds a collar 51 against the plate 48 in a manner keeping these parts in frictional contact. The collar 51 is pinned at 52 to rotate with the shaft. The type wheels 6 and 7, which may be made integral as illustrated in Fig. 3, are mounted 45 on the front end of this shaft 44.

Loosely mounted on the shaft 20 beneath the type wheels is a sleeve 53. The front end 50 of this sleeve carries a pair of toothed wheels 54 and 55 formed integrally therewith or otherwise fixed thereto. These wheels cooperate with the type wheels in a manner hereinafter described. A gear 56 fixed to the 55 inner end of the sleeve is in mesh with the gear 49, the type wheels 6 and 7 and toothed wheels 54 and 55 thereby being in positive driving connection.

As has been above described, the tape feed 60 wheels 10 and 11 are driven from the motor 14 through the frictional connection at 21 and their rotation is controlled by mechanism synchronized with the printing operations. Likewise, the type wheels 6 and 7 are driven 65 from the motor 14 through the frictional con-

nection at 43 and their rotation is controlled by the following mechanism synchronized with the printing operations.

An escapement wheel 57 fixed on the inner end of shaft 44 has cooperating therewith an escapement arm 58 secured to the free end 70 of an armature 59 pivoted at 60 between two pairs 61 and 62 of electro-magnets. The two lower magnets 61 are so connected in series in a local circuit 101, hereinafter described, 75 that both attract the armature 59 when a current is passed through this circuit. The two upper magnets 62 are so connected in series in a main circuit 99, hereinafter described, 80 that one attracts and the other repels the armature 59 when a current is passed through this circuit. The local circuit 101 through magnets 61 and through the bars 61' and magnets 62 serve to attract the armature 59 and hold it in whichever position it occupies, until 85 armature is effected by a current through the circuit 99. The polarization of the current through the circuit 99 is alternated, as hereinafter described, and the armature is pivoted one way and then the other by the magnets 62 at each polarization change in this 90 circuit.

The escapement wheel 57 has fifteen teeth and the type wheels 6 and 7 each has thirty 95 printing characters thereon. At each pulsation or change of polarity in the main circuit 99 through the magnets 62 the escapement 100 permits the escapement wheel and its shaft 44 to turn one-thirtieth of a full rotation, thus bringing the next character into printing position. The rotation of the type wheels is therefore synchronized with the pulsations or polarity changes in this main circuit.

The following means also synchronized 105 with the rotation of the type wheels and the pulsations in the main circuit 99 are provided for automatically and selectively performing the printing operations from the type on the wheels as such type pass the printing position. Respectively cooperating with the two type wheels are two press members 63 pivoted respectively to the free ends 64 of two 110 armatures 65 pivoted at 66. The free end 67 of each member 63 engages beneath the tape 3 and is shaped to raise the tape into printing 115 engagement with the type by a hammer blow action. This action is provided by the two wheels 54 and 55. Each of these wheels has thirty teeth 68 corresponding to the thirty 120 type on each type wheel. Each member 63 carries a finger 69 normally drawn into the path of the teeth 68 by means of a spring 70. This engagement is very slight and is limited by adjustable stops 71. The downward pivotal movement of each press member is also 125 limited by a pin stop 72.

The two armatures 65 cooperate with four electro-magnets 73 and 74. The bottom pair 73 is so connected in series in the local circuit 101 that both attract the two armatures 65 130

when a current is passed through this circuit. The top pair 74 is so connected in series in a main circuit 90, hereinafter described, that one attracts its armature 65 and the other repels its armature 65 when a current is passed through this circuit. Each armature 65 cooperates with two magnets 73 and 74 and when the machine is operating the local circuit 101 to the magnets 73 remains closed. 5 These magnets, in cooperation with bars 73' and magnets 74, serve to attract both armatures 65 and hold the fingers 69 out of contact with the teeth 68 when no current is passing through the circuit 90. When a current 10 of one polarity passes through the circuit 90 and magnets 74 one of these magnets will augment the action of its adjacent magnet 73 to more securely hold its armature 65 while the other magnet 74, being oppositely connected 15 in the circuit, will repel its armature 65 in a manner throwing its finger 69 into the path of the teeth 68. The type wheels and toothed wheels 54 and 55 being in constant rotation, a tooth 68 will engage the finger and quickly 20 swing the member 63 to press the tape against the corresponding character on the type wheel. The armature is thereafter immediately retracted by the magnets. It will therefore be seen that electrical impulses of 25 30 one polarity on the main circuit 90 will cause printing from one type wheel and impulses of the opposite polarity will cause printing from the other type wheel.

In Fig. 6 of the drawings, I have diagrammatically illustrated a transmitting mechanism cooperating with the printer comprising my invention. It should be understood that this transmitting mechanism is shown in its simplest form for illustrative purposes only. Commercial transmitting mechanisms of various types and operating on various principles are old and well known in the art and, obviously, any of such mechanisms can be applied to and used with my invention. 45

In Fig. 6 is illustrated a double-keyboard 75 comprising an inner contact member 76 and an outer contact member 77. A lead wire 78 connected to the contact member 76 passes through a battery 79 and from thence is grounded at 80. A lead wire 81 connected to the contact member 77 passes through a battery 82 and from thence is grounded at 80. It will be noted that the batteries 79 and 82 50 55 have their poles oppositely arranged whereby current passing through one such battery will be of opposite polarity from current passing through the other battery. Thirty double-ended keys 83 are mounted on the keyboard 60 and these keys are respectively connected by wires 84 to thirty contact segments 85 on a member 86. These keys are normally out of contact with the members 76 and 77 but may be depressed into contact with either of such 65 70 members. The outer ends of the keys repre-

sent the letter characters corresponding to the type wheel 7 and the inner ends of the keys represent the numeral characters corresponding to the type wheel 6.

Mounted on a shaft 87 and cooperating 70 with the member 86 is a trailer 88 adapted to contact with the segments 85 as the shaft rotates. A brush 89 engages the shaft and is connected to the main circuit 90. Also carried on the shaft 87 is a distributor wheel 91 having insulated segments 92. The edge portion of this wheel is trailed by a pair of current-reversing brushes 93 and 94 so arranged that one brush is always on a segment 92 while the other brush engages the wheel. The circuit from brush 93 passes through a battery 95 and from thence is grounded at 96. The circuit from brush 94 passes through a battery 97 and is then grounded at 96. It will be noted that these batteries have their poles oppositely arranged whereby current passing through one of the batteries will be of opposite polarity from current passing through the other battery. A brush 98 is in continuous contact with the wheel 91 and is connected 80 to the main circuit 90 through a hand switch 100. It will be understood that the shaft 87 can be rotated by any convenient source of power. 85 90

The main circuit 90 is always open except 95 when a key 83 is depressed and contact made through the corresponding segment 85 and brush 88. The main circuit 99 is always closed except when the switch 100 is open. In commercial practice several printers are 100 operated from a single transmitter. Each of these printers includes a local circuit 101, within which is a battery 102, extending through the local magnets 61 and 73, and a local circuit 103 for the motor and within 105 which is a battery 104. It is desirable that these circuits should be closed only when receiving from the transmitter. The following means is provided for automatically closing these local circuits when closing the transmitter switch 100 and for automatically opening the circuits when opening the switch 100. 110

A switch 105 in the local circuit 101 has a stationary contact 106 and a cooperating contact 107 on a lever 108 pivoted to the free 115 end of an armature 109 pivoted at 110. A spring 111 connected to the lever normally holds the lever in a position wherein a shoulder 112 thereon engages against a stop pin 113. In such position the free end of the lever projects into the path of a lug 114 on the gear 49 and the lug is adapted to engage the lever and open the switch as shown in Figs. 4 and 6. However, when the hand switch 100 is closed a pair of electro-magnets 115 in the 120 circuit 99 attracts the armature 109 and withdraws the lever from the path of lug 114 and the spring 111 thereupon closes the switch. The switch 105 remains thus closed as long 125 as the switch 100 is closed and is automatically 130

ly opened when the switch 100 is opened. The spring 111 is not strong enough to pull the armature 109 away from the magnets 115 even though the current through the magnets 5 is of a pulsating nature.

The circuit 103 includes a normally open switch 116. The local circuit 101 includes a pair of electro-magnets 117 having an armature 118 adapted to engage and close the switch 116 when the switch 105 is closed. Both local circuits 101 and 103 are therefore automatically controlled by the hand switch 100. The main circuits 90 and 99, after passing through their several electro-magnets, 15 are grounded at 119 and 120.

The operation of my improved mechanism, as illustrated herein, is substantially as follows: It is assumed that one or more receiving printers are connected to the transmitter through main circuits 90 and 99 as illustrated in Fig. 6 and that, switch 100 being open, the circuits are all open. When desiring to transmit, the transmitting operator closes the switch 100. A current is immediately transmitted through the circuit 99 from one brush 93 or 94 and this current excites the magnets 115 and withdraws the lever 108 from the lug 114. The spring 111 thereupon immediately closes the switch 105 of the local circuit 101. This circuit 101 thereupon (1) excites magnets 61 to hold the escapement 58 against operation, (2) excites magnets 73 to withdraw and hold the fingers 69 from the teeth 68, and (3) excites magnets 117 to close the motor circuit switch 116. The operator then starts the rotation of shaft 87, the distributor wheel 91 and brushes 93 and 94 thereupon causing change of polarity pulsations through the circuit 99.

All the circuits, except circuit 90, now being closed, the following operations are taking place. The motor is driving the gear 19 and tending to rotate the feed wheels 10 and 11 through the frictional connection at 21 and tending to rotate the type wheels 6 and 7 through the frictional connection at 43. The pulsating current passing through circuit 99 is oscillating the escapement arm 58 to rotate the type wheels and toothed wheels 54 and 55 in synchronism with the rotation of shaft 87. The speed of the motor is such that the gear 43 is rotated slightly faster than the gear 49. The pawl 38 is holding the tape feed wheels from rotating. The local magnets 73 are holding the press members 63 from the toothed wheels 54 and 55, and magnets 115 and 117 are operating to keep switches 105 and 116 closed.

The operator may now transmit any of the characters on the keyboard merely by depressing the corresponding keys 83. For example, to transmit and print character A, the operator depresses the key end marked A into contact with the member 77 and holds the same depressed until the brush 88 con-

tacts with the segment 85 connected thereto. The following circuit is thus established: key A, contact member 77, wire 81, battery 82, grounds 80 and 119, magnets 41, magnets 74, wire 90, brush 89, shaft 87, trailer 88, segment 85, wire 84, key A. The polarity of this circuit through the battery 82 is such that it causes the press magnet 74 of the numeral type wheel 6 to attract its armature 65. Both magnets 73 and 74 therefore cooperate to hold the front press member 63 from engaging the teeth of the wheel 54. The rear magnet 74 however, being oppositely connected in the circuit, repels its armature 65 in a manner throwing the finger 69 of its press member 63 into contact with a tooth of the wheel 55. In like manner, all contacts made with member 77 pass through battery 82 and cause printing from the letter type wheel 7. All contacts made with member 76 pass through battery 79, having its poles oppositely arranged, and cause printing from the numeral type wheel 6.

It will be understood that the distributor wheel 91 and the trailer 88 being mounted on shaft 87 assures the accurate synchronizing of the type wheels with the shaft 87 i. e., the type which is in printing position always corresponds to the character connected with the segment 85 engaged by the trailer 88. It will also be understood that the teeth 68 so correspond with the type that a tooth is always in proper position to engage the finger 69 and kick the press member and tape into printing contact with the character selected. The impulse through the circuit 90 also causes the magnets 41 to withdraw the pawl 42 and permit the feed wheels 10 and 11 to feed the tape the distance of one character. The magnets 74 and teeth 68 act together in such manner that the tape feeding and printing operations take place substantially simultaneously.

It is believed that the operation of the invention will be clear from the above description taken in connection with the drawings. The closing of the switch 100 by the transmitting operator automatically closes the circuits in all the receiving instruments on the line. Upon starting of the shaft 87, the type wheels are immediately rotated and continue to rotate during the entire transmitting period, the printing and tape feeding operations taking place so rapidly and synchronously therewith that no stopping or effecting of the type wheels is necessary. It is well known that the stopping and restarting of the printing wheel for each printing operation, as heretofore commonly practiced, consumes a large portion of the total operating time. My invention entirely eliminates these objections and obviously increases the printing capacity to a very considerable extent. As thus far experimentally developed, my invention herein illustrated

has successfully operated to print 9000 characters per minute, i. e., when the circuit 90 is held closed and all characters on the wheel are printed. This requires the type wheels to make 300 rotations per minute, and is the speed at which I have normally operated the machine. At this speed, the apparatus will normally operate to selectively print approximately 900 characters or approximately 150 words per minute. When the transmitting operation is completed, the operator needs only to open the switch 100 and the circuits in all the receiving instruments on the line immediately open automatically.

15 I claim:

1. In a printing telegraph, the combination of a character printing wheel, means including controlling means for continuously rotating the wheel at a definite speed, a member adapted to press a tape against the wheel to selectively print the characters thereof on the tape during such rotation, means synchronized with the controlling means and including mechanically driven means for causing instantaneous operation of the said member to print predetermined and selected characters without stopping the wheel, and synchronized means for automatically feeding the tape at such printing operations.

2. In a printing telegraph, the combination of a character printing wheel, means including an electro-magnetically operated escapement for continuously rotating the wheel at a definite speed, a press member, continuously operating means adapted to selectively move the member to press a tape against the wheel and cause printing of selected characters thereon during such rotation, means including electro-magnetic means synchronized with the escapement for causing the press member to be thus operated to print predetermined and selected characters without stopping the wheel, and synchronized means for automatically feeding the tape at such printing operations.

3. In a printing telegraph, the combination of a character printing wheel, means including controlling means for continuously rotating the wheel at a definite speed, a member adapted to press a tape against the wheel to selectively print the characters thereof on the tape during such rotation, a member driven synchronously with the printing wheel, means cooperating with the first member and adapted to engage the second member to cause a printing operation, means synchronized with the said controlling means for causing such engagement to print predetermined and selected characters without stopping the wheel, and synchronized means for automatically feeding the tape at such printing operations.

4. In a printing telegraph, the combination of a character printing wheel, means in-

cluding electrically controlled means for rotating the wheel at a definite speed, a press member, mechanically driven means adapted when engaged by the press member to move the member into printing contact with the wheel, means including electrically controlled means in synchronism with the first named electrically controlled means for causing the press member to selectively engage the mechanically driven means and print predetermined and selected characters from the wheel, and synchronized means for automatically feeding the tape at such printing operations.

5. In a printing telegraph, the combination of a character printing wheel, a wheel having positive driving connection therewith and provided with teeth respectively corresponding with the characters on the wheel, means including controlling means for continuously rotating the wheels at a definite speed, a member adapted to press a tape against the printing wheel to selectively print the characters thereof on the tape during such rotation, means cooperating with and causing printing operation by said member when moved into the path of said teeth, means synchronized with said controlling means for causing the second mentioned means to be engaged by predetermined teeth and thereby print predetermined characters, and synchronized means for automatically feeding the tape at such printing operations.

6. In a printing telegraph, the combination of a character printing wheel, a motor for rotating the wheel, an electric circuit, means in the circuit controlling the rotation of the wheel, an electric circuit synchronized with the first named circuit, means operative to print on a tape from said wheel, electro-magnetic means in the second named circuit, and means operated by the last named means for selectively controlling the operation of the second named means.

7. In a printing telegraph, the combination of a character printing wheel, means for rotating the wheel, an electric circuit, means in the circuit controlling the rotation of the wheel, an electric circuit synchronized with the first named circuit, electro-magnetic means in the second named circuit, an armature cooperating therewith, means pivoted to the armature, and a driven member adapted to kick the pivoted means into printing contact with a character on the wheel when permitted by the electro-magnetic means to engage the member.

8. In a printing telegraph, the combination of two character printing wheels, means for rotating the wheels, an electric circuit, means in the circuit controlling the rotation of the wheels, an electric circuit synchronized with the first named circuit, two electro-magnets oppositely connected in the second named circuit, two armatures respectively cooperating

therewith, two members respectively pivoted to the armatures, and driven means adapted to kick the members into printing contact with the characters on the wheels, the operative engagement of the members with the said driven means being controlled by the electro-magnets.

9. In a printing telegraph, the combination of two character printing wheels, a pair of press members respectively cooperating therewith, a pair of series and oppositely connected electro-magnets respectively controlling said members, the arrangement being such that currents of opposite polarity will have opposite effects respectively on the press members, means including an electro-magnetically operated escapement for continuously rotating the wheels at a definite speed, means synchronizing the operation of the first named electro-magnets with the escapement, and means for moving the selected press member to press a tape against the corresponding character on the wheel selected, the arrangement being such that the polarity of the circuit through the said magnets automatically selects the wheel and the current impulse selected determines the character printed.

10. In a printing telegraph, the combination of a character printing wheel, a motor frictionally connected to rotate the wheel, an electro-magnetically controlled escapement controlling the rotation of the wheel, means for pressing a tape into printing contact with the wheel, means including electro-magnetic means synchronized with the escapement for causing the first named means to press the tape against the corresponding character on the wheel while the wheel continues to rotate, and other synchronized means for automatically feeding the tape at such printing operations.

11. In a printing telegraph, the combination of a printing wheel having a plurality of characters thereon, a motor frictionally connected to rotate the wheel, and an electro-magnetically controlled escapement so controlling the rotation of the wheel that the characters thereon are consecutively brought into printing position synchronously with the pulsations or polarity changes in the circuit through the electro-magnet.

12. In a controlling mechanism, the combination of two electro-magnets connected in series and in the same direction, two cooperating and adjacent electro-magnets connected in series but in opposite directions, and two armatures therefor, one armature cooperating with one of the first named magnets and one of the second named magnets and the other armature cooperating with the remaining two magnets.

13. In a controlling mechanism, the combination of two electro-magnets connected in series and in the same direction, two cooper-

ating and adjacent electro-magnets connected in series but in opposite directions, and two pivoted armatures therefor having their pivots more closely adjacent the two first named magnets, one armature cooperating with one of the first named magnets and one of the second named magnets and the other armature cooperating with the remaining two magnets.

14. In a printing telegraph, the combination of two character printing wheels, a pair of press members respectively cooperating therewith, and a pair of series and oppositely connected electro-magnets respectively controlling said members, the arrangement being such that currents of opposite polarity will have opposite effects respectively on the press members.

15. In a printing telegraph, the combination of two character printing wheels, a pair of press members respectively cooperating therewith, a pair of series and oppositely connected electro-magnets respectively controlling said members, and another pair of series and like connected electro-magnets respectively operating on said members, the arrangement being such that a local circuit through the second pair of magnets will attract both press members and currents of opposite polarity through the first pair of magnets will have opposite effects respectively on the press members.

16. In a printing telegraph, the combination of a character printing wheel, means including a motor for rotating the wheel at a definite speed, a main circuit, a local circuit, a local circuit for the motor, means including electrical means in the first named local circuit and synchronized with the main circuit and the rotation of the wheel for causing selective printing from the wheel, means in the main circuit for causing the first local circuit to close when the main circuit is closed and to open when the main circuit is opened, and means in the first local circuit for controlling the motor circuit.

17. In a printing telegraph, the combination of a character printing wheel, a motor for rotating the wheel, a main circuit, a local circuit, an electrically controlled escapement, in both said circuits for controlling the rotation of the wheel, a local circuit for the motor, means including electro-magnetic means in the main circuit for causing the first named local circuit to close when the main circuit is closed and to open when the main circuit is opened, and electro-magnetic means in the first named local circuit for controlling the motor circuit.

18. In a printing telegraph, the combination of a character printing wheel, a motor for rotating the wheel, a main circuit, a local circuit, electro-magnetic means in both said circuits for controlling the rotation of the wheel, a local circuit for the motor, a nor-

mainly closed switch in the first named local circuit, mechanical means driven by the motor for opening the switch and holding it open, means including electromagnetic
5 means in the main circuit for withdrawing the switch beyond the path of said mechanical engagement when the main circuit is closed and into said path when the main circuit is opened, and electro-magnetic means
10 in the first local circuit for controlling the motor circuit.

19. In a printing telegraph, the combination of a character printing wheel, a motor for rotating the wheel, a frictional driving
15 connection between the motor and the wheel, a main circuit, a local circuit for the motor, electrically controlled means in the main circuit for controlling the rotation of the wheel, a second main circuit synchronized with the
20 first main circuit, means including electrical means in the second main circuit for causing selective printing from the wheel, and means for causing the motor circuit to close when the first main circuit is closed and to open
25 when the first main circuit is opened.

In testimony whereof I affix my signature.
ANDREW T. MacCOY.
